UNITED STATES PATENT OFFICE.

EDWARD G. PARKHURST, OF HARTFORD, CONN., ASSIGNOR TO HIMSELF
AND THE PRATT & WHITNEY COMPANY, OF SAME PLACE.

PACKING-BOX FOR AMMUNITION.

SPECIFICATION forming part of Letters Patent No. 237,406, dated February 8, 1881.

Application filed October 11, 1880. (No model.)

To all whom it may concern:

Be it known that I, EDWARD G. PARKHURST, of Hartford, in the county of Hartford and State of Connecticut, have invented certain new and useful Improvements in Packing-Boxes for Ammunition; and I do hereby declare that the following is a full, clear, and exact description thereof, whereby a person skilled in the art can make and use the same, reference being had to the accompanying drawings, and to the letters of reference marked thereon.

Like letters in the figures indicate the same parts.

15 My invention relates to an improvement in the construction of boxes in which the ammunition for machine-guns is carried for use in the field.

As at present used the ammunition, consisting of metallic shells charged with powder and ball, is first packed in pasteboard or other similar boxes containing about twenty cartridges, and these cases are packed in boxes or sliding drawers fitting into the caisson of 25 the gun, which are designed to hold a certain number of the pasteboard cases, so as to fill them and prevent movement during transportation. It frequently happens, however, that part of the pasteboard cases are used out of 30 one of the boxes, in which case the remainder are loose in the box and become destroyed or damaged by shifting about.

The object of my improvement is to provide a means for retaining either the whole or part 35 of the interior cases in place within the packing-box, so that they will be prevented from shifting their position while the box is transported.

In the accompanying drawings, illustrating 40 my invention, Figure 1 shows a perspective view of one of the boxes or drawers withdrawn from a caisson, or an independent box with the cover removed. Fig. 2 is a detached view of the sliding partition or gate which is adapted 45 to fit into the grooves in the sides of the box.

A is the packing-box.

B B, &c., are the interior cases containing the ammunition. The sides and ends of these cases are shown by dotted lines in Fig. 1, and

the box, when full, is designed to hold three 50 full lengths, or forty-five in all. In the drawings nineteen are shown, fifteen in their ordinary position when the box is filled and four standing on their ends.

C is a removable partition, which can be 55 slipped into any pair of a series of grooves, D, in the sides of the box A. When the box is entirely full the partition is placed in the first grooves from the farther end, as shown in the drawings, lying close to the end A'. When part 60 of the ammunition is removed, and it is desired to confine the remainder, the remaining cases are packed so as to fill the box up to any pair of grooves, and the partition placed in those grooves, so as to hold them in place. The distances between the grooves are designed to be such as to include the full length of the cases, or one or more thicknesses, as shown in the drawings, so that the cases can be packed flatwise or endwise to fill the space. 70

For the purpose of easily removing the partition C when the box is full there is a socket, E, forming a handle, by which it is lifted. The end of the box has a corresponding notch or opening, F, so that the fingers can be placed 75 in the socket E.

The partition C is attached to the box by a cord of sufficient length to allow of its being placed in any of the grooves, so that it shall not be dropped or lost. This cord is shown 80 at G in the drawings. When the partition is placed at the end of the box this cord is coiled up and placed in the recess H.

Besides holding the ammunition in place in the partially-emptied box, the partition C 85 serves the purpose of facilitating the withdrawal of the cases from the full box. The drawing out of the partition from its position at the end, when the box is full, leaves a space for the fingers to enter and lift the cases readily, while without this space the removal of the first cases is a difficult operation. 90

What I claim as my invention is—

1. The box A, provided with the grooves D and the removable partition C, adapted to 95 lie against the end of the box when the same is wholly filled, and to be removed to the other grooves to hold and confine the ammunition.

cases when the box is partially filled, substantially as described.

2. The combination of the removable interior partition, C, having a handle-socket, E, 5 with the box A, having its end provided with the notch F, substantially as described.

3. The partition C, having the recess H for

holding the cord G, in combination with the end of the box, which closes the receptacle for the cord, substantially as described.

EDWARD G. PARKHURST.
